UNITED STATES PATENT OFFICE.

WILLIAM COOMBES, OF WOLLATON, ENGLAND.

MEANS FOR CUTTING FABRICS INTO LENGTHS OR PORTIONS.

Original application filed March 5, 1927, Serial No. 173,017, and in Great Britain November 10, 1925.
Divided and this application filed November 3, 1927. Serial No. 230,843.

This invention comprises improvements in or relating to means for cutting fabrics into lengths or portions. This is a division of application Serial Number 173,017, filed

5 March 5, 1927.

The invention has particular, though not exclusive, reference to fabric which is produced in a continuous piece and subsequently cut into the requisite lengths to form towels, 10 cleaning cloths and other like articles. In the manufacture of fabric for producing such articles it is customary at predetermined intervals to discontinue for a certain specified time the lay or feed of the yarn 15 which extends transversely across the longitudinally extending threads and binds together such threads, thus producing lengths of fabric connected at intervals by comparatively narrow transverse bands composed 20 solely of longitudinally extending threads. This, in fabric composed of warp and weft, produces weftless bands between predetermined lengths of complete or "solid" fabric, and for convenience these bands will 25 hereinafter be referred to as weftless divisions.

A feature of the present invention consists in the provision of a machine for cutting fabrics into lengths or portions comprising a rotary fabric feeding frame, a 30 rotary fabric cutting device, and means associated with the rotary feeding member for engaging successively with weftless portions of the fabric and anchoring said fabric so as to be severed at said weftless portions.

Another feature resides in the provision of an intermittently rotatable fabric feeding frame having elements thereon which serve the dual purpose of intermittently with- 40 drawing a predetermined length of fabric from the supply and anchoring the fabric in position for being acted upon by the cutter.

Further features reside in the provision of means for alternately moving the cutter into and out of cutting position, and means for enabling the length or quantity of fabric withdrawn and severed at each operation to be variably adjusted as required.

50 Other features reside in the construction and arrangement of machine and method of operation as hereinafter more fully described and set forth in the appended claims.

For the purpose of more fully describing 55 the nature of this invention, reference will

now be made to the accompanying drawings, wherein:

Figure 1 is a side elevational view of a machine in accordance with this invention.

Figure 2 is an elevational view of part of 60 the machine shown in Figure 1 looking at the opposite side thereof.

Figure 3 is a plan view showing the cutters used on the machine.

Figure 4 is a section through the rotating 65 frame showing means for adjusting the diameter thereof.

Figure 5 is a side elevational view showing a further modified construction.

Figure 6 is a plan view of Figure 5. 70

In the one method of carrying out the invention as illustrated in the drawings a machine will be described, wherein fabric lengths or portions are simultaneously cut from a plurality of pieces each withdrawn 75 from a separate supply roller or beam, but it is to be understood that the machine is equally effective in severing portions from a single fabric piece.

The fabric rollers 1 (four of which are 80 illustrated) are mounted one above the other to rotate within brackets or bearings 2 adjustably or otherwise carried at the rear part of the machine frame 3, the brackets at either or both ends of the rollers preferably being hinged or formed with a hinged or displaceable portion for facilitating the withdrawal of an empty roller or beam and the insertion of a fresh roller.

Mounted to rotate intermittently on a 90 horizontal axis at a suitable distance in front of and preferably at a lower level than the rollers 1 is a frame member 4 which comprises a plurality, say for example six, of equally spaced radially extending end arms 95 4^a between which at or near their extremities are transversely or horizontally extending bars 5, somewhat in the nature of a yarn winding mill, each of said horizontal bars having a series of U-shaped wire elements 6 or their equivalent projecting radially from its outer face. A second bar 7 is fixed to extend alongside each bar 5 and is spaced a short distance from said bar.

The fabric lengths 8 with weftless divisions 9 are withdrawn from the rollers 1 and suitably guided forwardly to extend over the above named rotatable frame 4, said fabric being adapted to depend in front of the foremost bars 5, 7 of said frame. Pref. 100 105 110

erably the fabric 8 is guided to the rotating frame and the separate lengths of said fabric maintained out of contact with each other prior to reaching the frame 4 by suitably disposed and adjustably mounted rollers or the like 10.

The arrangement is such that as the frame 4 rotates in the direction of the arrow shown in Figure 1 the wire elements 6 carried by each bar 5 as it travels over the upper-most position in its circular path comes into engagement with a weftless division 9 in all of the superposed fabric lengths 8 passing over said arm, said elements 6 being caused to project up through the several weftless divisions and, by continued rotation of the frame, exert a forward pull upon the several fabric lengths, the rotation being continued until the bar 5 having the wire elements 6 which project through the fabric is located in the most forward position with the side arms 4^a carrying same horizontal, when the frame 4 is held from rotation.

In this position a suitable cutter such as hereinafter described comes into operation to sever the several fabric pieces at the weftless divisions immediately above the wire anchoring elements 6 carried by the foremost bar 5, such cutter operating between said bar and the bar 7 spaced a short distance above same.

Immediately this cutting operation has been effected the frame 4 continues to rotate to draw forwardly and downwardly a further number of superposed fabric pieces to be severed, the rotation of the frame being intermittent to permit of the cutting operations. It is to be understood that at each rotative movement of the frame 4 certain of the anchoring elements 6 function to engage with and project through weftless divisions in each of the fabric lengths 8 thus drawing off at each motion the required length to be severed from each fabric piece.

The intermittent rotation of frame 4 may be effected from disc crank or eccentric 11 carried by shaft 12 driven from any convenient source of power, said crank carrying a pivoted pawl 13 projecting upwardly therefrom and held in engagement by a suitable spring 14 with a ratchet wheel 15 keyed on the central spindle 16 of frame 4 the number of teeth on the ratchet coinciding with, and being angularly spaced to the same extent as the arms 4^a. By this arrangement one half of each revolution of the crank 11 effects a rotative movement of the frame 4 to the extent of one sixth of a complete revolution while during the other half of the revolution of the crank the frame is held stationary and the pawl 13 is moved down to engage with another tooth on the ratchet 15 prior to the next movement of the frame. A suitable stop 17 limits the lateral movement of the pawl 13 under the influence of its spring.

During the stationary period of the frame the cutting operation is in effect, and in one method of accomplishing this a plurality of rotary cutting discs 18 are rotatably mounted upon separate laterally aligned axes, said discs being arranged to overlap each other to a suitable extent. These cutters are mounted upon a suitable plate or frame 19 which is slidably adjustable within or upon another plate or frame 20 in a direction 75 at right angles to the axis of the rotary frame 4, the adjustment being effected by any suitable means such as a screw member 21.

The plate or frame member 20 is also slideable to and fro within suitable guides 22 carried by or forming part of the machine frame 3, this reciprocative sliding movement of the frame 20 being required in order to move the cutters 18 alternatively into and out of engagement with the fabric 8, the cutters being brought into engagement with the fabric when the frame 4 is stationary and moved away from said fabric after the cutting operation and before the frame 4 commences to rotate to bring further fabric into position for cutting.

This reciprocative movement of the frame 20 with cutters 18 may be effected from the shaft 12 through the intermediary of a second disc crank 23 carried by this shaft, a horizontally extending rod or link 24, an upwardly extending centrally pivoted lever 25 pivotally connected at its lower end to rod 24 and at its upper end by pin and slot connection to the sliding frame 20. The operation is so timed that while the pawl 13 is rotating the frame 4 the frame 20 is away from the fabric and while said pawl 13 is being brought down and the frame 4 is maintained stationary, the frame 20 is moved towards the fabric so as to enable the cutters to sever same.

Simultaneous rotating of the cutting discs may be effected in any desired manner such, for example, as by mounting a small motor 26 on the frame 19 moving with the cutters and transmitting motion from the motor to the cutters by driving band 27 which passes over a pulley 28 on the axis of one of the 115 cutters; a second endless band 29 being passed over pulleys 30 on the axes of the several cutters.

To retain the frame 4 from displacement while cutting is being effected a small spring pressed pin 31 (Figures 2 and 5) may be provided adapted to engage with one of a series of peripheral notches 32 in wheel 33 fixed upon the central spindle 16 of the frame, the number of said notches coinciding with the number of radiating arms 4^a of the frame.

Instead of employing a plurality of cutting discs as above the cutting of the fabric may be accomplished by a single cutter. 130

One method of effecting this is illustrated in Figures 5 and 6.

A cutting disc 34 is rotatably carried at the one or forward extremity of an arm 35 which arm is pivoted at its rear end on a pin 36. The arm 35 with cutter is adapted to be intermittently displaced so as to move the cutter alternately to each side of the machine and in its travel across the machine 10 to cut the fabric, the angle of movement of the arm being sufficient to move the cutter through the fabric and clear of same at each stroke, this movement being timed so that while the frame 4 is being rotated the arm 35 15 is stationary, and while the frame 4 is stationary the cutting stroke is effected.

In one method of accomplishing this the arm 35 has pivotally connected thereto at a suitable position in its length the one end of 20 a rod 37, the other end of said rod being connected to a disc crank or eccentric 38 keyed upon a vertical rotatable shaft 39 suitably carried by the machine frame or parts thereon. On this shaft 39 is keyed a gear 25 wheel 40 which is adapted to mesh intermittently with a gear wheel 41 having teeth on one half of its circumference only. This half cog 41 is keyed upon a further vertical rotating shaft 42 having fixed thereon a pulley 43 over which passes a driving band 44 which band also passes over a second pulley 45 on the before mentioned shaft 12. The arrangement is such that as the shaft 42 with half cog 41 rotates, the latter transmits 30 during one half of its revolution rotary motion to the gear wheel 40 and the disc crank rotating therewith, during which movement the cutter arm 35 is, through the medium of the connecting rod 37, angularly displaced 35 40 to traverse the cutter across the machine. During the second half of the revolution of the half cog 41 which coincides with the rotative movement of the frame 4—no motion is transmitted to the cutter arm by reason of there being no intermeshing engagement between the half cog 41 and the gear 45 wheel 40.

The necessary rotary movement of the cutter 34 is, in this arrangement, also advantageously effected from a small motor 46 suitably carried at the rear or pivoted end of the arm 35 so as to be moved with said arm, a driving belt 47 extending from a pulley of the motor to a pulley 48 fixed to the cutter axis.

In order to vary the effective diameter of the cutting frame 4 so as to adapt the machine for use in cutting varied lengths of fabric, i. e. fabric in which the distance between the weftless divisions vary, the transversely extending arms 5 together with the adjacent arms 7 are so mounted as to be adjusted radially of the arms 4^a means being preferably provided whereby the whole of 65 the arms 5 and 7 are adjustable simultane-

ously to an equal degree. This may be effected as shown in Figure 4 by mounting upon the central spindle 16 a rotatable sleeve 49 having fixed at each end thereof a bevel 50, each bevel intermeshing with a series of other bevelled sleeves 51 fixed at the near end of screw threaded spindles 52 rotatably borne within suitable brackets or members on the inner side of each of the radial arms 4^a of the frame 4. Where six 70 radial arms 4^a are provided at each end of the frame six screwed spindles 52 and an equal number of smaller bevels 51 would be furnished at each end of said frame. Two of the screwed spindles 52 pass through internally screw threaded holes in each transversely extending arm 5 and the arrangement is such that by transmitting rotation to any one of the screwed spindles 52 by means of a handle 53 rotative movement is 75 transmitted to the sleeve 49 and bevels carried thereby, which in turn transmits rotation to the whole of the bevels 51 and spindles 52, and by reason of the screwing engagement between said spindles 52 and bars 80 5 the latter simultaneously move either inwardly or outwardly in accordance with the direction of turning of the handle. It will be appreciated that the spindles 52 on the one end of the frame are provided with 85 right hand screw threads while the spindles at the other end of the frame have left hand threads.

Any suitable means may be provided for applying tension to the fabric lengths 8 100 withdrawn from rollers 1. For example the spindles or the rollers may be frictioned by springs 1^a or friction may be applied to the surfaces of the fabric rollers.

The severed portions of fabric may be 105 received upon a continuously travelling belt 54 (Figure 1), a guide bar 55 being, if desired, provided for ensuring that the severed fabric in falling is properly laid upon the belt 54.

I claim:—

1. A machine for cutting a fabric with weftless divisions into lengths comprising an intermittently rotatable fabric feeding frame, a rotary cutter, means carried by said frame for successively engaging with weftless portions of the fabric and feeding same to the cutter, said fabric engaging means also anchoring the fabric so as to be severed at the weftless divisions, and means 115 for moving the cutter into cutting position while the feeding frame is stationary and out of such position while the frame is rotating.

2. A machine for cutting into lengths 125 fabric formed with weftless divisions, comprising a rotary fabric feeding frame, means for intermittently rotating said frame, elements projecting radially from said frame at a plurality of positions around its circum- 130

ferential path of movement, said elements successively projecting through weftless divisions in the fabric and serving the dual purpose of withdrawing fabric from its supply and anchoring same in position for cutting, a rotary cutter, means for moving said cutter into engagement with the fabric while the feeding frame and fabric are stationary and means for withdrawing said cutter while the fabric is being fed.

3. A machine for cutting into lengths fabric formed with weftless divisions, comprising supports for a plurality of rolls of such fabric, a rotary fabric feeding frame, means for guiding the fabrics from said rolls to said frame, means for transmitting intermittent rotation to said frame, said fabrics passing on to said frame in superposed relations, elements carried by said frame for successively engaging with superposed weftless divisions in the fabric, said elements effecting simultaneous withdrawal of the fabric from their supply rolls and anchoring same in position for cutting, a rotary cutting device, means for moving said cutting device into engagement with the superposed fabrics while the rotary frame is stationary and means for displacing said cutter

from its cutting position while said frame is rotating.

4. In a machine for cutting into lengths fabric formed with weftless divisions, a rotatable fabric feeding frame, a pawl and ratchet device transmitting intermittent rotation to said frame, radially projecting elements on said feeding frame, said elements engaging with the weftless portions in the fabric and functioning both to draw said fabric from the supply and anchor same during cutting, rotary cutting means, means for transmitting rotary motion to said cutter, means for moving said cutter alternately towards and away from the fabric, said last named means working in conjunction with the means for transmitting intermittent rotation to the feeding frame so as to move the cutter away from the fabric during feeding and into engagement with said fabric while the feed is stationary, spring-influenced means for preventing movement of the fabric feed during cutting, and means for adjusting the effective size of the rotary feeding frame so as to enable the size of the fabric portions withdrawn and severed to be adjusted.

WILLIAM COOMBES.
